BEACON LIGHT

Alwin Kost, Portland, Oreg., assignor to Kost Incorporated, Portland, Oreg., a corporation of Oregon

Application February 17, 1940, Serial No. 319,562

8 Claims. (CL 177—352)

This invention relates to beacon lights of the flasher type commonly used for aeroplane landing fields air courses, lighthouses, marine beacons and the like.

An object of this invention is to provide an efficient beacon light of the flasher type that will provide very frequent flashes of light, that will cover the entire area surrounding the beacon, that will be visible from all points in the area it covers and that will not have any blind spots.

Another object is to provide a beacon which employs a mechanical movement of the type disclosed in my prior Patent No. 2,246,689, issued June 24, 1941.

Another object is to provide a beacon comprising a dome carrying a plurality of lights and connected with mechanism for simultaneously imparting to said dome an oscillatory and a tilting movement whereby a combined horizontal and vertical sweep will be imparted to each beam of light emanating from said dome.

Another object is to provide a beacon having means for changing the color of the beams of light projected therefrom.

Other objects of the invention will be apparent from the following description taken in connection with the accompanying drawings.

In the drawings

Fig. 1 is a vertical sectional view of one type beacon light apparatus constructed in accordance with this invention.

Fig. 2 is a sectional view on a reduced scale substantially on broken line 2—2 of Fig. 1, parts being shown in plan and parts in section taken substantially on broken line 3—3 of Fig. 1.

Fig. 4 is a diagrammatic view showing means for changing the color of the beacon lights and electrically controlled operating means for these color changing devices.

Fig. 5 is a fragmentary detached elevation of a part of the color changing device.

Fig. 6 is a vertical sectional view with parts omitted of another type of beacon light apparatus having means for varying the amplitude of gyratory movement of the lamp portion thereof.

Fig. 7 is a view in cross section taken through the yoke 31 and pivot member 38 of Fig. 1.

Fig. 8 is a view in cross section taken through the yoke 116 and pivot 115 of Fig. 6.

Like reference numerals designate parts throughout the several views.

Referring to Figs. 1 to 3, I show beacon light apparatus comprising an upright housing formed of an upper section 10 and a lower section 11.

The lower section 11 is secured to a base 12 by screws 13. The upper section 10 has a conical upper end portion 14. The base 12 and lower housing section 11 may be relatively detached to provide access to the interior of the housing section 11. The two housing sections 10 and 11 are fastened together by a bracket member 15 that is disposed chiefly within the upper housing section and projects downwardly into the lower housing section and is secured to both of said housing sections by screws 16. The bracket 15 forms a support and bearing for certain operating devices, hereinafter described, which are disposed within the housing.

15 These operating devices are adapted to impart a combined oscillatory and tilting movement to a light carrying dome as hereinafter described.

The bracket 15 provides bearings for an upright tubular shaft 17 within which is positioned another shaft 18. The shaft 18 is also preferably tubular to provide a passageway for electrical conductor wires 19.

20 The tubular shaft 17 is fixedly connected with a sleeve 20 so that said sleeve will rotate with the shaft 17. The sleeve 20 has an oblique circular plate portion 21 rigid with the upper end thereof. The plate portion 21 has a circular flange 22 extending perpendicularly therefrom. An inner bearing race member 23 is supported

25 exteriorly of the flange 22. Ball bearings 24 are operatively positioned between the inner bearing race 23 and an outer bearing race 25. The race 25 is supported within a cylindrical portion 26 of an inverted cup 27 that is provided centrally within a circular swash plate 28.

30 The swash plate 28 forms a base to which is secured a semi-spherical dome 29. A plurality of tubular lamp receptacles 30 are provided in the dome 29 and a lamp 31 is provided in each lamp receptacle. The inner end portions 32 of the lamp receptacles 30 are properly shaped and silvered to form light reflectors. Suitable lenses 33 are provided at the outer ends of the lamp receptacles 30. The lenses 33 are suitably shaped

35 to converge the rays of light and form light beams that are visible the maximum distance possible with the intensity of light used. Preferably means, as hereinafter described are provided for positioning light conductive color screens of different colors over the lenses 33. I find that five lamps arranged as shown in Figs. 1 and 2 are satisfactory in operation. Obviously a greater or less number of lamps than this may be used. 40 Preferably a fan 34 driven by an electric motor

5 that is built into said fan is provided within the dome 29 for cooling purposes.

The upper end portion of the shaft 18 is positioned substantially centrally within an inverted cup shaped member formed by a downwardly extending cylindrical flange 36 that extends within the flange 22. A yoke 37, see also Fig. 7, is pivotally mounted in the flange 36 and extends diametrically across the same. The upper end portion of the shaft 18 is connected with this yoke by a pivot member 38 positioned at right angles to the axis of the yoke 37. The yoke 37, see also Fig. 7, and pin 38 thus provide a universal joint connection between the shaft 18 and swash plate 28. The sleeve 17 is rotated and serves as a means to tilt the swash plate and impart a wobbling movement thereto. A collar 39 prevents upward movement of sleeve 17. The shaft 18 is oscillated and oscillates the swash plate back and forth simultaneously with its tilting movement.

The means for rotating the sleeve 17 comprises an electric motor 40 having a sheave 41 connected by a belt 42 with another sheave 43 on a shaft 44. A pulley 45 on the shaft 44 is connected by a belt 46 with a sheave 47 on a shaft 48. The shaft 48 has a bevel gear 49 that meshes with another bevel gear 50 on the tubular shaft 17 completing the driving connection thereto. Power for oscillating the shaft 18 is taken off of the tubular shaft 17. The means for taking off this power and converting it into oscillating motion comprises an eccentric member 51 secured on tubular shaft 17 and connected by a combined eccentric yoke and link 52 and pivot 54 with a gearwheel 53. The gearwheel 53 is mounted on a bearing 55 and meshes with another gearwheel 56 that is secured on the shaft 18. Operation of eccentric devices 51 and 52 will impart oscillations to gearwheel 53 and this will oscillate gearwheel 56 and shaft 18.

Figs. 4 and 5 show diagrammatically a control for a device to change the color of the beams of light. The color device comprises a circular band 57 extending around the dome 29 over the four lenses 33 adjacent the swash plate 28. This circular band 57 is movable rotatively and is guided in guide and support means 58. This circular band 57 has openings 59 adapted to register with the lenses 33 in the normal operation of the beacon. Said band 57 also has a section 60 of colored light conductive material adjacent each opening 59, the sections 60 preferably being red. The colored sections 60 may be moved over the lenses 33, and in some instances are so moved to provide colored beams of light for signaling or for use in foggy weather.

The means for moving the circular band 57 may be controlled in different ways. I have illustrated electrically actuated manually operated remote control means. This means, as herein disclosed, comprises a reversible motor 61, Fig. 4, having a driving pinion 62 on its shaft 63 that meshes with a gear 64 on the band 57. Current to the motor 61 is supplied from source of supply conductors 65, 66 and 67 that are connected through three pole switch 68 with other conductors 69, 70 and 71. Switch 68 is moved into a closed position by electromagnet 72 when said electromagnet is energized and is moved by gravity into an open position when electromagnet 72 is not energized. Conductors 69 and 70 are connected with the two switch arms 73 and 74 respectively of a reversing switch. The arms 73

and 74 are movable by mechanical engagement with a lug 75 on the circular band 57 and by a mechanical connection with another switch, as hereinafter described. The two pairs of contact members of the reversing switch are connected by conductors 76 and 77 with the motor 61. The third conductor 71 from switch 68 is connected directly with the motor 61.

A starting circuit for momentarily energizing the solenoid 72 and putting into operation the motor circuit just described is provided. This starting circuit comprises a remotely disposed manual control switch 78, having one terminal connected by conductor 79 with one of the source of supply conductors, such as conductor 66 and the other terminal connected by conductor 80 with one terminal of solenoid 72. The other terminal of solenoid 72 is connected by conductor 81 with one of the source of supply conductors 67. A hold-in circuit is provided for solenoid 72. This hold-in circuit comprises a pivotally mounted switch arm 82 operated by the lug 75 of the band 57. The switch arm 82 is mechanically connected by link means 82' with the switch arms 73 and 74 of the reversing switch. Two spaced apart contact members 83 and 84 are provided for engagement by the movable end of contact arm 82 and are electrically connected with each other by conductor 85. A conductor 86 electrically connects the contact members 83 and 84 with the same terminal of solenoid 72 that is connected with the switch 78. Another conductor 86' connects contact arm 82 with conductor 70.

In operation, when the beacon is showing white light the several parts illustrated in Fig. 4, will be in the positions therein shown. If it is desired to show the colored light then the remote control starting switch 78 is momentarily closed manually. The momentary closing of starting switch 78 closes a circuit through solenoid 72 and this closes switch 68. The closing of switch 68 establishes electrical connections to the motor 61 to operate said motor 61 in the proper direction to move the color screen carrying member 57 clockwise, Fig. 4, until the color screens 60 are positioned over the lenses 33. As soon as starting switch 68 is closed a hold-in circuit for switch 68 is established from conductor 67 through conductor 81, solenoid 72, conductors 86 and 85, contact 83, arm 82 and conductor 86' to conductor 70. This allows switch 78 to be immediately opened and insures that the motor 61 will continue to operate until the hold-in circuit to the solenoid 72 is broken. This hold-in circuit will be momentarily broken by engagement of the lug 75 with the switch arm 82 just before the circular band 57 reaches the limit of its clockwise movement. When lug 75 engages switch arm 82 it will move switch arm 82 to the left. This will first momentarily break the hold-in circuit and cause switch 68 to drop open and break the motor circuit due to the disengagement of switch arm 82 from both of the contacts 83 and 84. Immediately thereafter it will re-establish the hold-in circuit by moving arm 82 into engagement with contact member 84 as the motor coasts to a stop. At this same time movement of the switch lever 82 will move the reversing switch levers 73 and 74 to reverse the motor connections through this reversing switch so that when the motor circuit is again closed the motor 61 will run in a reverse direction. After the color screens 60 have been posi-

tioned in front of the lenses 33, as above described, they may be moved back into the position shown in Fig. 4, by momentarily closing the starting switch 78 to run the motor 61 in a reverse direction until the lug 75 engages the switch arm 74 and throws the reversing switch and the hold-in switch and stops the motor.

The manual control starting switch 78 may be located at any remote point from which the beacon is to be controlled. The color screens may be used in case of fog or as a danger signal or for any other reasons. Obviously the screens 60 may be red or any other color or color screens of different colors may be used in the same beacon.

The fan 34, shown in Fig. 1, helps to dissipate the heat produced by the lamps 31 by drawing in outside air under the shield 9 and through the openings 8 in the top portion of the housing 29 and forcing said air out through openings 7 in the bottom portion 28 of the housing. The shield 9 helps to exclude moisture from the housing 29 and also directs the air over said housing in such a manner as to keep the housing cool.

The universal tilting movement imparted to the housing 29 will impart a continuous up and down movement to the beams of light from the radial light tubes 30. At the same time the oscillating movement will impart horizontal movement back and forth to these same beams of light and the resultant will be that the beam from each radial tube 30 will follow a curved path which will be determined by the ratio of the gears 53 and 56 and by the amount of movement provided by the eccentric disc 51. This provides very efficient beams that are visible from all positions around the beacon.

The axial tube 30 will direct a beam of light upwardly and this beam will be projected in substantially the shape of a cone. Obviously light tubes 30 may be provided at other angles in the housing if desired.

Fig. 6 shows a form of the invention in which means is provided for adjusting the amplitude of angular movement of the swash plate.

Said Fig. 6 discloses a frame 87 providing bearings for a rotatable tubular shaft 88 within which is disposed an oscillatory shaft 89, also preferably tubular. A driven shaft 90 is connected by gearwheels 91 and 92 with the tubular shaft 88 for rotatively driving the same. An eccentric 93 on the tubular shaft 88 is connected by a combined yoke and link member 94 with a crank pin member 95 on a gearwheel 96. The gearwheel 96 meshes with another gearwheel 97 on the shaft 89 and oscillates said shaft 89.

The tubular shaft 88 is sufficiently larger than the shaft 89 to leave an annular space 100 between these two shafts and a sleeve 101 is operatively disposed in this annular space. The shaft 89 oscillates in the sleeve 101 and the sleeve 101 rotates with the tubular shaft 88. The tubular shaft 88 has longitudinal slots 102 in the upper end portion thereof and the sleeve 101 carries a bracket arm 103 and two radial lugs 104 that all project outwardly through the slots 102. The lugs 104 engage with ball bearing means 105 in a bearing cup 106. The bearing cup 106 is mounted on and supported by an upright screw 107 by which said bearing cup is vertically adjusted. A worm wheel 108 is secured to the screw 107 and meshes with a worm 109 on a shaft 110 whereby the screw 107 may be turned.

Any suitable control means, not shown, may be provided for operating the shaft 110 from any desired location.

The bracket arm 103 is connected by a link 111 with a bearing cradle 112 within which are ball bearing and race means 113 for providing a rotatable connection with an inverted cup member 114.

The upper end portion of oscillatory shaft 89 has a universal joint connection with inverted cup member 114 through pin 115, yoke 116 and flange means 117.

Bearing cradle 112, see Fig. 8, is supported from tubular shaft 88 by forked bearing cradle support 119, one fork of which is shown in Fig. 6. Forked bearing cradle support 119 is connected with cradle 112 by pivots 118, the pivots 118 being in axial alignment with pin 115 in the position shown in Fig. 6.

From the foregoing description it will be understood that the bearing cradle is supported jointly by support 119, pivots 118, link 111 and sleeve 101 and that the angle of inclination of the cradle 112 relative to shafts 88 and 89 may be adjusted by vertical adjustment of the sleeve 101. Variation of this angle inclination will vary the amplitude of tilting movement of any light carrying dome means that is secured to inverted cup member 114.

The foregoing description and accompanying drawings clearly disclose a preferred embodiment of my invention but it will be understood that this disclosure is merely illustrative and that changes may be made in the invention without in the scope and spirit of the following claims.

I claim:

1. An illuminated beacon comprising a dome; a plurality of lamps in said dome positioned to project beams of light in different directions from said dome; universal joint bearing means positioned at an incline and movably supporting said dome for universal tilting movement; driving means operatively connected with said dome supporting means for imparting universal tilting movement to the dome; adjusting means connected with said dome supporting means adapted to adjust the incline of said universal joint bearing means whereby the amplitude of tilting movement is adjusted; and dome oscillating means connected with said dome for oscillating said dome simultaneously with the universal tilting movement thereof.

2. Apparatus of the class described, comprising a housing; an upright shaft supported for oscillation in said housing; shaft oscillating means connected with said shaft; a body to be oscillated; universal joint means connecting said body with said oscillatory shaft whereby said body will be oscillated by said shaft; a tubular shaft on said oscillatory shaft; driving means connected with said tubular shaft; and bearing means interconnecting said body and said tubular shaft and inclined relative to said tubular shaft and supporting said body for universal tilting movement.

3. Apparatus of the class described, comprising a housing; an upright shaft supported for oscillation in said housing; shaft oscillating means connected with said shaft; a body to be oscillated; universal joint means connecting said body with said oscillatory shaft whereby said body will be oscillated by said shaft; a tubular shaft on said oscillatory shaft; driving means connected with said tubular shaft; ball bearing

means connected interconnecting said body and said tubular shaft and inclined relative to said tubular shaft and supporting said body for universal tilting movement; and means for adjusting the angle of inclination of said ball bearing means.

4. An illuminated beacon comprising an upright driven tubular shaft; a bearing member supported on the upper end portion of said shaft in a plane oblique to the axis of the shaft; beacon lamp means supported by said bearing member for universal tilting movement by rotation of said bearing member; and an oscillatory shaft positioned within said tubular shaft and connected with said beacon lamp means for oscillating said beacon lamp means simultaneously with the tilting movement thereof.

5. Apparatus of the class described, comprising a rotatably driven upright tubular shaft; a bearing member supported on the upper end portion of said shaft in a plane oblique to the axis of the shaft; a body supported by said oblique bearing member for universal tilting movement by rotation of said tubular shaft and said bearing member; an oscillatory shaft positioned within said tubular shaft; and connected with said body providing for oscillation of said body simultaneously with the tilting movement thereof.

6. An illuminated beacon comprising an upright driven tubular shaft; a bearing member pivotally mounted on said tubular shaft for angular movement on an axis transverse to the axis of the tubular shaft; means for adjusting said bearing member on its axis; and a lamp dome supported by said bearing member for tilting

movement by rotation of said bearing member.

7. An illuminated beacon comprising a rotatably driven upright tubular shaft; a bearing member pivotally mounted on the upper end portion of said tubular shaft for angular adjustment on an axis transverse to the axis of said tubular shaft; means for adjusting said bearing member to vary the angle of inclination of the same relative to said shaft; beacon lamp means supported by said bearing member and arranged to be tilted therewith by rotation of said tubular shaft; and an oscillatory shaft positioned within said tubular shaft and connected with said beacon lamp means for oscillating said beacon lamp means simultaneously with the tilting movement thereof.

8. Apparatus of the class described comprising a rotatably driven upright tubular shaft; a bearing member pivotally mounted on the upper end portion of said tubular shaft for angular adjustment on an axis transverse to the axis of said tubular shaft; a vertically movable sleeve within said tubular shaft and rotatable therewith; a link connecting said sleeve with said bearing member; means for vertically adjusting said sleeve to thereby vary the angle of inclination of said bearing member relative to said shaft; a body supported by said bearing member and arranged to be tilted therewith by rotation of said tubular shaft; and an oscillatory shaft positioned within said tubular shaft and said sleeve and connected with said body for oscillating said body simultaneously with the tilting movement thereof.

35 ALWIN KOST.
